No. 11,873

July 20, 1880

N.S. Vedder Troy N.Y.

Cut 223.

UNITED STATES PATENT OFFICE.

CYRUS A. HODGES, OF TROY, NEW YORK, ASSIGNOR TO OTIS G. CLARK AND DANIEL D. BUCKLIN, EXECUTORS OF THE LAST WILL OF N. S. VEDDER, DECEASED.

DESIGN FOR A BOX-STOVE.

SPECIFICATION forming part of Design No. 11,873, dated July 20, 1880.

Application filed June 14, 1880. Term of patent 3½ years.

To all whom it may concern:

Be it known that I, CYRUS A. HODGES, of the city of Troy, in the county of Rensselaer and State of New York, have invented and produced a new and original ornamental Design for Box-Stoves, of which the following is a specification, reference being had to the accompanying print of a stove having my said new design.

The principal feature of this invention is the design for the side plate and front plate, consisting of the central tablet, A, surrounded by the rectangularly-zigzag fillet B, having the series of scallops c along the inner edges and outer edge ornaments, d, the panel surface E, and the border G, composed of the fillet h, with zigzag corner parts, i, and the inside and outside ornamentations, j and k, the outer

scallop ornamentation, l, and the intervening surface m, having the corner ornaments, n, all shaped and arranged together so as to appear substantially as represented in the aforesaid print.

What I claim as my invention is—

The design for the side plate and front plate, composed of the parts A, B c d, E, and G h i j k l m n, all shaped and arranged as shown and described.

In testimony whereof I hereunto set my hand, in the presence of two subscribing witnesses, this 9th day of June, 1880.

CYRUS A. HODGES.
